UNITED STATES PATENT OFFICE.

RALPH BIRD, OF JERSEY CITY, NEW JERSEY.

CRADLE.

SPECIFICATION forming part of Letters Patent No. 609,654, dated August 23, 1898.

Application filed April 9, 1898. Serial No. 677,063. (No model.)

To all whom it may concern:

Be it known that I, RALPH BIRD, of Jersey City, in the county of Hudson and State of New Jersey, have invented a new and Improved Cradle, of which the following is a full, clear, and exact description.

This invention is a cradle constructed so that it may be readily folded into compact form when not in use, thus permitting it to be transported with great facility and stored away in a small space when desired.

This specification is the disclosure of one form of my invention, while the claims define the actual scope thereof.

Reference is to be had to the accompanying drawings, forming a part of this specification, in which similar characters of reference indicate corresponding parts in all the figures.

Figure 1 is a perspective view of the invention. Fig. 2 is a plan view of the same in folded position. Fig. 3 is a detail section of the invention on the line 3 3 of Fig. 1, and Fig. 4 is a fragmentary view of one of the braces.

The cradle has head and foot arches 5 and 6, respectively, each fixedly mounted on a base-rail 7, which rails are in turn hinged to transversely-extending bars 8, located, respectively, alongside of the rails 7. The bars 8 are connected with each other, so as to form a rigid frame, by means of crossed rods 9, each provided with a retractile spring 10, by which proper tension is maintained. Fixed to each end of each bar 8 is a brace 11 and 12, respectively. These braces are therefore four in number, and are located two at each side of the cradle. The two braces at each side of the cradle are pivotally joined to each other by means of pins 13. The ends of the braces 11 and 12 opposite the ends that are attached to the bars 8 are provided with slots 14, wherein are loosely fitted pins 16, carried one at each side of each arch 5 and 6. By these means the arches are mounted on a framing so that the arches may be thrown down to horizontal position or may be raised to perpendicular position. When the arches are raised to perpendicular position, as shown in Fig. 1, the pins 16 lie in the outer ends of the respective slots 14; but when the arches are thrown down to horizontal position the pins 16 move inwardly along

the slots 14, and the base-rails 7 swing on their hinges so as to be raised from their first position, while at the same time the braces 5 and 6 in moving downward with the arches 5 and 6 slightly rock the bars 8. The arches 5 and 6 are held in raised position by means of two dog-plates 17, which are carried, respectively, on the braces 12 at the outer portions of the slots 14 therein. The dog-plates 17 are mounted so that they may drop into the slots and engage with the coacting pins 16, thus preventing the pins from moving through the slots, and consequently holding the arches in perpendicular position. To drop the arches, the plates 17 are thrown up to disengage the adjacent pins 16, and consequently the arches may be moved inward and downward.

Hinged to the upper portion of each arch 5 and 6 is an extension-standard 18, and each standard 18 is capable of extending perpendicularly from the arches, as shown in Fig. 1, or of swinging downward to lie alongside of the arches, as shown in Fig. 2. Fitted in each standard 18 is a casing 19, carrying a bolt 20 and also a spring 21 to throw the bolt downward. The upper end of each bolt 20 is provided with a head 22, whereby the bolt 20 may be manipulated. The bolt 20 of each standard 18 extends downward into a cavity 23 in the extension-standard 18. Each arch 5 and 6 is provided with a rigid keeper 24, said keepers projecting downwardly from the outer side of each arch and projecting inwardly at their upper ends into the respective cavities 23, so as to be engaged by the bolts 20, and thus to hold the standards 18 raised above the arches. By lifting the bolts 20 the keepers 24 are disengaged and the standards 18 may be thrown inward, as indicated by the dotted lines in Fig. 3, to the position shown by full lines in Fig. 3.

Each extension-standard 18 is provided with a rigidly-attached plate 25, located on its inner side and having a stud 26 projecting inward therefrom. The studs 26 pivotally carry slings 27, which are attached to the four corners of a rectangular frame 28. This frame carries a flexible web 29, forming the body of the cradle.

The cradle thus constructed may be adjusted to operative position, so that the child

may be held and rocked by the swinging of the slings 27 on the projections 26. When it is desired to fold the cradle, the bolts 20 should be lifted to disengage the keepers 24 and the extension-standards 18 moved inward and downward. Then the dog-plates 17 should be lifted to disengage the adjacent pins 16, whereupon the arches may be folded inward and downward over the body of the cradle, which, being formed of fabric, collapses on the brace-rods 9 and assumes the position indicated in Fig. 2. This places the cradle in very compact form, and it may be handled and stored with great facility.

Having thus described my invention, I claim as new and desire to secure by Letters Patent—

1. In a cradle, the combination of head and foot arches, a base-rail, on which each arch stands, a bar hinged to each base-rail and running parallel therewith, brace-rods joining the bars to each other, additional braces fixed to the bars and having sliding connection with the respective head and foot arches, an extension-standard carried by each arch, a keeper attached to each arch and projecting into proximity with the standard thereof, a bolt carried by each standard and removably engaging the keeper thereof, a sling pivotally attached to each extension-standard, and a cradle proper hung from the slings.

2. In a folding cradle, the combination of an

arch forming a supporting member, a keeper attached rigidly to the outer side of the arch and extending upward and inward therefrom, an extension-standard pivotally mounted at the upper portion of the arch and having a cavity capable of receiving a portion of the keeper, and a sliding bolt carried in the extension-standard and movable to engage and release the keeper.

3. In a cradle, the combination of head and foot members, a base-rail on which each member is mounted, a bar hinged to each base-rail and extending parallel therewith, two braces attached to each bar, the braces having slotted ends, two pins carried by each of said head and foot members and respectively fitting into the slots of the braces, and two dog-plates mounted on two of the braces and capable of engaging the adjacent pins so as to hold the head and foot members in perpendicular position.

4. In a folding cradle, the combination of head and foot members adapted to support the cradle, a bar with which each of said members is hingedly connected, and braces attached to the bars and having sliding connection with said head and foot members.

RALPH BIRD.
